METHOD OF AND MACHINE FOR HEEL
BREASTING

Erastus E. Winkley, Lynn, Mass., assignor to
United Shoe Machinery Corporation, Borough
of Flemington, N. J., a corporation of New
Jersey

Application January 11, 1940, Serial No. 313,409

36 Claims. (Cl. 12—47.1)

This invention relates to the art of heel-breasting and is particularly concerned with apparatus for breasting attached heels which are to be provided with breast surfaces that are substantially straight vertically, and concave laterally, of the heel and with an improved method of breasting such heels.

The commercial breasting of attached heels of the aforementioned type is at present accomplished by means of a reciprocating knife that is forced through the heel from top-lift surface to breast line, either manually or with the aid of power means. The blade of the knife is curved to give the desired lateral concavity of breast surface, and its cutting edge is arc-shaped to conform, at least approximately, to the shank portion of the shoe at the breast line. The operation of forcing the knife through the heel is laborious and also somewhat injurious to the heel structure and adjacent shank portion of the shoe due to the considerable pressure applied. The individual pieces of leather or leatherboard which form the heel are each compressed by the knife, as it passes, and subsequently expand so as to present a "stepped" and irregular breast surface on the heel. The smoothing-up of such a surface in the following scouring and finishing operations involves the expenditure of considerable time and labor.

Difficulty is encountered also in producing a breast surface which merges with the sides of the heel along lines that are substantially straight when viewed from the side of the shoe. This is particularly the case with heels that widen appreciably from top lift to heel seat and great care in grinding the knife, jacking the shoe, and in manipulating the knife in the breasting operation is required to obtain the straight side lines demanded by the trade. In some instances, the breast edges must be straightened with a hand knife after the breasting cut has been made.

An object of this invention is the provision of a machine for cutting smooth breast surfaces, having straight side edges, on attached heels of the aforementioned type in an easy and efficient manner, and without distortion or injury to the heel or shoe structure adjacent thereto. In the attainment of this object there is utilized, as a feature of this invention, a novel kind of breasting tool that operates widthwise, or transversely, of the heel, progressively from top-lift surface to breast line, and without interference with other portions of the shoe, to cut a smooth and substantially straight breast surface of the desired lateral concavity on the heel. Other features of

this invention are to be recognized in means for supporting an attached heel for movement across the cutting edge of the breasting tool, from top-lift surface to breast-line center, along a curved path of pre-selected and variable radius to obtain straight lines at the breast edges; in novel means for arresting the feeding movement of the heel to the tool at the breast line, in means for imparting a combined swinging and predetermined shifting movement of the heel relative to the tool for completing the breasting cut from breast-line center to each opposite end of the breast line in a manner to maintain the breast edges straight throughout their entire lengths, and also in means for preventing the aforesaid swinging and shifting movement during the initial feeding movement of the heel across the tool.

Another feature of this invention is to be found in the provision of a novel method for breasting attached heels by first forming on the heel a breast surface extending from top lift to breast-line center and subsequently completing the breast surface to each opposite end of the breast line by means of relative sidewise and separating movements of the heel and the cutting edge of a breasting tool at the breast line.

The above and other features of this invention will now be more particularly described with reference to the accompanying drawings, where- 30 in a preferred embodiment of the invention is illustrated, and thereafter pointed out in the appended claims.

In the drawings,

Fig. 1 is a side elevation of a heel-breasting machine embodying this invention;

Fig. 2 is an end view of the machine with some of the elements broken away to show the breasting tool;

Figs. 3, 4 and 5 are perspective views of component parts of the machine;

Fig. 6 is an end view of a part of the work carriage looking in the direction of the arrows VI—VI, Fig. 1;

Figs. 7 and 8 are partial side views of the machine showing two relative positions of the breasting tool and work carriage assumed during operation of the machine;

Fig. 9 is a plan view of a part of the machine looking in the direction of the arrows XI—XI, Fig. 1;

Fig. 10 is a perspective view of parts of the machine showing the relative positions of the breasting tool and the heel at the final stage of a breasting operation;

Fig. 11 is a partial plan view of a portion of

the machine illustrating the relative positions of the breasting tool and the heel at an intermediate stage of a breasting operation;

Figs. 12, 13 and 14 are diagrammatic views illustrating the action, and position, of the breasting tool during the breasting operation;

Fig. 15 is a side elevation of a completely breasted heel;

Fig. 16 is a partial plan view of a modified cutter head and breasting tool assembly;

Fig. 17 is an end elevation of the assembly shown in Fig. 16;

Fig. 18 is a plan view of the breasting tool employed in the modified assembly of Fig. 16; and

Figs. 19 and 20 are diagrammatic views illustrating the operation of the modified breasting tool of Fig. 16.

In the drawings, 10 is a main frame on which is mounted a driving motor 12 and a cutter-head frame 14. A shaft 16, carrying a cutter or breasting tool 18 having teeth 19, is journaled in the cutter head frame and is connected to the motor by means of a belt 20.

Secured to the upper part of the main frame, and extending outwardly therefrom, is a bearing bracket 22 in which is journaled a shaft 24. At its lower end the shaft is connected to a supporting member 28. The shaft and supporting member are suspended on the bearing bracket by means of a coil spring 26 engaging a nut 27 threaded on the upper end of the shaft. Mounted on the supporting member is a longitudinally extending slide-rod 30, provided with a stop collar 31, on which is slidably mounted a carriage 32. At its lower end the carriage is guided on the supporting member by a guideway 34 (see Fig. 3). The supporting member has, at its lower extremity, an extended portion 42 to which is secured a downwardly extending shaft 36 journaled in a bearing boss 38 of a box-like frame member 40 fixed to the lower part of the main frame 10.

The extended portion 42 of the supporting member 28 rests on an arm 44 which is pivoted to the frame member 40 by means of a pin 46. A suitable self-aligning bearing 62 is interposed between the upper surface of the pivoted arm and the extended portion of the supporting member. Also pivoted to this frame member is a plate 48, journaled on a pin 50, and interposed between the upper surface of this pivoted plate and the lower surface of the pivoted arm are rollers 52 carried by a yoke member 56 which is adjustable lengthwise by means of a screw 58 and a knurled adjusting knob 60. Mounted on the lower surface of the pivoted plate is a roller 64 which bears against the upper surface of a cam 66 journaled on the shaft 36. The cam rides with its cam surface 61 on a fixed cam roller 68 carried by an upstanding part 70 of the frame member 40. Secured to the extended portion of the supporting member is an angular arm 72 having a downwardly projecting portion provided with a slot 74. The cam carries a radially extending rod 78 which projects through the slot 74.

The supporting member 28 and carriage 32 carried thereby are, by virtue of the arrangement of the parts just described, swingable about the common vertical axis of the shafts 24 and 36 and are supported vertically by the cam roller 68 and the spring 26. On swinging of the supporting member the cam 66 is turned by the arm 72 and the rod 78. The cam surface 61 is shaped so that the swinging of the supporting member to either side from the position shown in Figs. 1 and

2 results in a gradual lifting of the supporting member and its associated parts. The amount of lift for any given angle of swing can be varied by turning the knob 60 to change the position of the rollers 52. By suitable adjustment of the nut 27 the major part of the weight of the supporting member and the other parts carried thereby may be transferred to the spring so that the load carried by the cam roller is reduced to a minimum and the lifting action of the cam 66 thus facilitated.

The purpose of the aforementioned swinging and lifting actions and the necessity for providing for variation in the amount of lifting under different operating conditions will be explained below.

Referring to Figs. 1, 3, 4 and 5, a carrier 82 is mounted for turning or tilting movement relative to the carriage 32 on roller studs 80 which engage arcuate slots 84 in the carrier. The carrier has projecting portions at one end on which are mounted a heel-locating plate 85 and toe-positioning elements 90 and 92 (see Fig. 6). The heel-locating plate is adjustably mounted on the carrier by means of an adjusting slot 86 and a locking screw 88. A clamping member 94 controlled by a clamping screw 93 and having a last-engaging portion 96 and a toe clamp 98 is supported on the carrier. In Fig. 1 a lasted shoe S is shown in outline with the clamping member engaged therewith and with its heel H located by the heel-locating plate and its forepart positioned by the toe-positioning elements.

The carrier is provided with a plate 100 which is guided for arcuate adjustment thereon by means of a guide plate 101 and arcuate slots 102 in which are positioned locking screws 104. Secured to the plate 100 is a block 106 at the outer end of which an arm 108 is mounted for angular adjustment by means of a pivot pin 110 and a clamping screw 112. The arm is formed with a cam slot 114 in which is positioned a cam roller 120 journaled on a pin 116 secured to a part 118 of the main frame 10. As the carriage 32 is slid along the slide rod 30, toward the breasting tool or cutter 18, the carrier will be turned in a clockwise direction on the roller studs 80 so as to tilt the heel away from the cutting edge of the breasting tool (see Figs. 1, 7, 8 and 12), due to the camming action of the roller 120 in the cam slot 114. By changing the angular position of arm 108 the amount of this turning or tilting action may be varied.

At its lower end the carriage 32 is provided with an upstanding portion 122 in which is slidably received an adjusting screw 124, controlled by a nut 125. The adjusting screw is also supported by a portion 128 extending from the carriage and is kept from rotating by means of a yoke member 126 secured thereto and engaging a carriage portion 130 (see Figs. 4 and 9). Secured to the inner end of the adjusting screw is an upstanding block 132 and an arcuately shaped stop-engaging member 134 for cooperating with an adjustable stop 140 mounted on the frame member 40. Adjustably mounted in the upper portion of this block is a control rod 136 having a downturned end slidable in a slot 142 in a plate 138 secured to the frame member. This plate is provided with an arcuate surface 139 over which the end of the control rod may travel during a certain stage of the operation of the machine, as will be explained below.

The supporting member 28 is provided with a projection 144 which is adapted to engage one

or the other of two stops 146 and 148 mounted on the frame member 40 (see Fig. 11).

In the operation of the machine a shoe, the heel of which is to be breasted, is first clamped on the carrier 32 and an initial line-up and adjustment of the heel is made by means of the heel-locating plate 85. The toe-positioning elements 90 and 92 are also set to accommodate the forepart of the shoe. In this initial lining-up the carrier may be tilted by adjustment of the plate 100 so that the heel is properly positioned with respect to the breasting tool or cutter 18. It will be understood that the heel will be so positioned that the breasting tool just clears, or removes a very small chip from, the preformed top lift T.

The breasting tool 18 comprises a substantially conical element which is hollow and has its open end or base facing toward the shoe. The cutting teeth 19, which are preferably saw-like in character, are arranged in a circular series about the base of the breasting tool and the axis of the tool is inclined at an angle with respect to the general direction of movement of the shoe and its heel during the breasting operation. Thus the plane including the circular series of teeth is inclined to the breast surface to be cut, as shown in Fig. 1, and the cutting edge formed by the teeth curves away from the heel in two directions (see Figs. 13 and 14). With the cutter rotated at a relatively high speed a clean and smooth breasting cut can be made on the heel with very little effort on the part of the operator and with no distorting or damaging effect on the heel or adjacent shoe portions.

Referring to Figs. 7 and 8, in the former the carrier 82 is shown in the position it assumes at the beginning of a breasting cut and at the point where the breasting tool has just passed through the top lift of the heel being breasted. Upon continued movement of the carriage 32 along the slide rod the parts eventually assume the position shown in Figs. 8 and 14. At this point the cutting edge of the breasting tool has been brought to the center of the breast line Bl at the shank portion Sh by movement of the heel over the tool. Engagement of the stop-engaging element 134 with the stop 140 prevents further movement of the carriage, carrier and heel toward the cutter. During this initial feeding movement the downturned end of the control rod 136 engages the side walls of the slot 142.

The heel H is a relatively high built-up heel of the so-called Cuban type and widens appreciably adjacent its upper or heel-seat portion (see Fig. 14). In order that the outer edges E of the breast surface B being cut may appear as straight lines, when viewed from the sides of the heel (see Fig. 15), it is necessary that the heel be passed across the cutting edge of the breasting tool in a path which is slightly convex lengthwise of the shoe. This is due to the fact that as the curved cutting edge of the tool reaches the widened upper portion of the heel the points of contact of the curved cutting edge with the outside surface of the heel become progressively nearer to the front or forepart of the shoe (see Fig. 13). Thus, if the heel were fed across the cutting edge along a straight path, the breast edges would be curved forwardly of the shoe. In the present machine, however, as the heel is fed to the tool by movement of the carriage 32, a tilting movement is imparted to the carrier 82 and heel so that the heel is moved across the cutting edge of the breasting tool

along a curved path. The breast surface (see Fig. 12) thus produced is slightly convex lengthwise of the shoe and the amount of curvature is just sufficient to make the breast edges straight.

5 As explained above, the tilting of the heel is accomplished by means of the arm 108 mounted on the carrier and the fixed cam 120, and the curvature of the path may be varied by suitable angular adjustment of the arm.

10 Referring to Fig. 14, the heel and breasting tool are shown in the positions they assume upon completion of the initial feeding movement just described. The heel breast has been substantially completed with the exception of small portions X-X on each side of the breast-line center which have not been reached due to the fact that the shank portion curves away from the cutting edge of the breasting tool. In order to complete the breasting cut on each side of the breast-line center and to the outer ends of the breast line at the shank portion, the heel is now swung sidewise of the cutter to each side of the center of the breast line, as illustrated in Figs. 10 and 11. In Fig. 11 the carriage 32 has been swung to the right until the stop 144 on the supporting member engages the stop screw 146. The cutter 18 has now been brought to one of the outer ends of the breast line, and upon reverse swinging movement to the positions indicated in broken lines of Fig. 11, with the stop 144 engaging the stop screw 148, the breasting cut is likewise completed on the other side of the breast-line center. In Fig. 10 the completion of a breasting cut is shown when the carriage was first swung to the broken line position of Fig. 11.

15 The axis of the shafts 24 and 36, about which the parts swing, is located rearwardly of the stop 140, and during these swinging movements the curved stop-engaging member 134 is held by the operator against this stop. Thus, by appropriately shaping the part 134, the heel can be made to move relatively to the cutting edge of the tool 18 along a path of a curvature equal to that of the shank. The swinging movements just mentioned are permitted as the control rod 136 has been moved beyond the groove 142 in the plate 138 at the completion of the initial feeding action so that its downturned end just clears the curved front face 139 (see Fig. 9, dotted lines). After the breasting cut has been completed on each side of the breast-line center the carriage is returned to its central position and the shoe and heel are withdrawn from the breasting tool with the control rod 136 again entering the groove 142.

20 As the carriage 32 and its associated carrier 82 are swung to complete the breasting cut, as just explained, a lifting movement is also imparted to these members. The purpose of this lifting movement is to continue and maintain the straightness of the breast-line edges throughout their entire length. Referring to Figs. 12, 13 and 14, it will be seen that if the heel were to be moved along an arc, the chord of which is substantially normal to the plane of the drawing of Fig. 12, which would be substantially the path of movement of the heel during the aforementioned swinging movement were no lifting or transverse shifting of the heel H away from the tool effected, that the breast-line edge would be curved rearwardly of the shoe since that portion of the curved cutting edge of the tool which is adjacent the center of the breast line would be projected through to the

outer edges of the heel breast. By appropriate lifting of the carriage, together with the carrier and the heel supported thereby, it is possible to compensate for this undesirable effect and to complete the breasting cut in such a manner that the straight edges produced by the initial arcuate feeding of the heel are continued throughout the entire lengths of the breast edges E. As explained above, the cam 66 and its associated mechanism are provided for producing this lifting action, and the adjustable rollers 52 make it possible to vary the amount of lifting to adapt it to any particular set of working conditions.

Concisely stated, the breasting of the heel in this machine is accomplished by an initial feeding movement of the heel across the curved cutting edge of the breasting tool along a path which is somewhat arcuate in character and such as to insure that the curved cutting edge will produce a slightly concave breast surface the edges of which are straight, followed by a combined sidewise and separating movement of the heel relative to the tool for completing the breasting cut on each side of the breast-line center in such a manner as to maintain the straightness of the breast edges.

Thus, in accordance with another aspect of this invention, the breasting of attached heels of the type herein considered is carried out in a novel manner. In a broader sense this improved method for breasting attached heels consists of first breasting the heel from top lift to breast-line center and then completing the breast surface to each opposite end of the breast line by causing relative sidewise movement of the heel and the cutting edge of the breasting tool at the breast line. More specifically, the initial breasting of the heel from top lift to breast-line center is effected by feeding the heel across the curved cutting edge of a transversely operating breasting tool along a path which is arcuate in character, and such that the curved cutting edge will produce a slightly concave breast surface the edges of which are straight, while the subsequent completion of the breast surfaces is accomplished by means of a combined relative sidewise and separating movement of the heel and tool of such a character as to insure the continuance of the straightness of the side edges of the breast surface down to the breast line ends.

In Fig. 15 a completely breasted heel is shown in which the edges E are perfectly straight and the breast, which is substantially straight vertically, is curved slightly lengthwise of the heel, as shown by the dotted line B. The action of the cutting tool 18 with its saw-like teeth 19 is such that the breast surface produced is very smooth and free from irregularities. The edges of the breast surface are straight and no hand-trimming work is necessary; also, due to the smoothness of the surface produced, very little, if any, scouring is required.

As will be seen from Fig. 13, the breasting tool produces a substantially vertically straight surface that is slightly concave laterally of the heel, which is the usual practice. Where the radius of curvature of the breast surface is relatively large, as is most commonly the case, the conical cutter 18 is large enough to receive the forepart of the shoe with ample clearance provided for the sidewise swinging movement of the heel and the breasting tool can cut entirely from top-lift surface to heel-breast line without interference with

other portions of the shoe. This is an important aspect of this invention because it makes possible the breasting of attached heels by means of a high-speed cutter operating transversely of the heel and the production of breast surfaces of superior smoothness, with little effort on the part of the operator and no damage or distortion to the heel or adjacent shoe portions.

In some instances, however, it is desired to cut a heel breast having a relatively small radius of curvature, in which case a conical cutter of appropriate shape would interfere with the sole of the shoe before the breasting cut could be completed. For work of this kind a modified type of breasting tool or cutter which also operates transversely of the heel, and in a manner similar to that of the breasting tool 18, is provided.

Figs. 16, 17 and 18 illustrate such a modified type of tool. The cutter head frame 14, in addition to the shaft 16, also journals a shaft 150. The shaft 150 is provided with a crank 151 which drives a crank arm 152, secured to the shaft 16, through the medium of a connecting rod 154. Secured to the end of the shaft 16, and in place of the breasting tool 18, is a modified tool or cutter 156. When the shaft 150 is rotated by the motor 12 through the belt 20 the shaft 16, together with the tool 156, is rapidly oscillated. The modified tool comprises an arcuate blade 158, of the desired curvature, having at its front edge a series of teeth 159.

In the operation of this modified type of breasting tool the teeth are oscillated back and forth across the front of the heel being breasted, in the manner shown in Fig. 19, the tool but partially clearing the breast surface at each end of its stroke. This tool, similar to tool 18 previously described, is capable of cutting from top-lift surface to breast line without interference with other shoe portions and produces a smooth breast surface. The heel of the shoe is fed across the cutting teeth 159 in exactly the same manner as described above in connection with the preferred form of breasting tool 18, and the sidewise swinging of the heel to complete the breasting cut, together with the lifting of the heel during the swinging movement, is carried out in the same manner and for the same purposes as previously explained. When this type of tool is to be used the cutter head frame and motor are positioned on the main frame 10 so that the axis of the shaft 16 is substantially aligned with the general direction of movement of the heel for breasting, and suitable bolt holes (not shown) are provided on the main frame for securing the motor and cutter head frame in this position.

Having described the invention, what is claimed as new and desired to be secured by Letters Patent of the United States is:

1. A heel-breasting machine comprising, in combination, a breasting tool having a plurality of teeth adapted to cut transversely of an attached heel and constructed and arranged to produce a substantially vertically straight and laterally concave breast from lift surface to breast line without interference with other portions of a shoe, and means for supporting a shoe for movement of its heel against said tool to breast said heel.

2. A heel-breasting machine comprising, in combination, a rotary breasting tool adapted to cut transversely of an attached heel and constructed and arranged to produce a substantially vertically straight and laterally concave breast from lift surface to breast line without interference with

ference with other portions of a shoe, and means for supporting the shoe for movement of its heel against said tool to breast said heel.

3. A heel-breasting machine, comprising, in combination, a saw-like breasting tool adapted to cut transversely of a heel constructed and arranged to produce a substantially vertically straight breast on an attached heel from lift surface to breast line without interference with other portions of a shoe, and means for supporting a shoe for movement of its heel against said tool to breast said heel.

4. A heel-breasting machine comprising, in combination, a breasting tool having a circular series of cutting teeth providing a cutting edge and constructed and arranged to cut a substantially vertically straight breast on an attached heel from lift surface to breast line without interference with other portions of a shoe, and means for supporting a shoe for movement of its heel against said cutting edge in a direction inclined substantially with respect to a plane including said cutting teeth to breast said heel.

5. A machine for breasting attached heels comprising a breasting tool having a cutting edge consisting of a plurality of teeth adapted to operate transversely of an attached heel and constructed and arranged to cut a substantially vertically straight and laterally concave breast on an attached heel from lift surface to breast line without interference with other portions of a shoe, and means for supporting a shoe for movement of its heel against said tool to breast the heel.

6. A heel-breasting machine comprising a breasting tool comprising a curved cutter having a series of teeth providing a cutting edge adapted to operate transversely of an attached heel from lift surface to breast line without interference with other portions of a shoe, and means for supporting a shoe for movement of its heel against said tool to breast the heel.

7. A heel-breasting machine comprising a rotary breasting tool comprising a curved cutter having a circular series of teeth providing a cutting edge adapted to operate transversely of an attached heel from lift surface to breast line without interference with other portions of a shoe, and means for supporting a shoe for movement of its heel against said tool to breast the heel.

8. A heel-breasting machine comprising an oscillatory breasting tool comprising a curved cutter having an arcuate series of teeth providing a cutting edge adapted to operate transversely of an attached heel from lift surface to breast line without interference with other portions of a shoe, and means for supporting a shoe for movement of its heel against said tool to breast the heel.

9. A heel-breasting machine comprising, in combination, a breasting tool having a cutting edge constructed and arranged to cut a substantially vertically straight and laterally concave breast from top-lift surface to breast line on an attached heel, and means for supporting a shoe for movement of its heel across said cutting edge along a curved path to breast said heel.

10. A heel-breasting machine comprising, in combination, a breasting tool having a cutting edge adapted to cut transversely of an attached heel, and means for supporting a shoe for movement across said cutting edge along a curved path that is convex rearwardly of the heel, for breasting the heel of said shoe from top-lift sur-

face to breast-line center, and laterally of said tool, for completing the breasting of said heel to the opposite outer ends of the breast line.

11. A heel-breasting machine comprising, in combination, a breasting tool having a cutting edge constructed and arranged to cut a concave breast surface on an attached heel, and supporting means for a shoe movable to feed the shoe heel across said cutting edge from top-lift surface to breast-line center, said means also being arranged for swinging said heel sidewise of said tool to complete a breasting cut to each outer edge of the heel at the breast line.

12. A machine for breasting attached heels comprising, in combination, a breasting cutter having an arcuate series of cutting teeth providing a curved cutting edge, and means for supporting and moving an attached heel across said cutting edge from top-lift surface to breast line, said means being constructed and arranged to tilt said heel toward said cutter as said breast line is approached so that the traces of said curved cutting edge on the opposite sides of said heel are substantially straight lines.

13. In a machine for breasting attached heels which widen appreciably from top lift to breast line, the combination with a breasting tool having a curved cutting edge adapted to cut transversely of a heel, of feeding means constructed and arranged for feeding an attached heel across said cutting edge to breast said heel from top lift to breast line in such a manner that the breast surface produced by said tool will have edges which are straight when viewed from the sides of the heel.

14. A machine for breasting attached heels comprising, in combination, a tool having a curved cutting edge adapted to cut transversely of a heel, means for feeding an attached heel which widens appreciably from top-lift to breast line to the cutting edge of said tool along a path that is slightly convex forwardly of the heel, means for swinging said heel sidewise of said tool when said tool reaches the breast-line center to complete the breasting cut along the entire breast line of the heel, and means for moving said heel away from said tool during said sidewise swinging, the actions of said feeding means, said swinging means and said moving means being such as to cause the curved cutting edge of said tool to produce a breast having straight side edges.

15. A heel-breasting machine comprising, in combination, a breasting tool having a cutting edge adapted to cut transversely of an attached heel, and shoe-supporting means movable to pass the heel of a shoe across said cutting edge for breasting said heel from top-lift surface to breast-line center, said supporting means also being movable to swing said heel sidewise, and to shift said heel transversely, of said tool for completing the breasting of said heel to the opposite outer ends of the breast line.

16. A heel-breasting machine comprising, in combination, a breasting tool having a cutting edge adapted to cut transversely of an attached heel, and shoe-supporting means movable to pass the heel of a shoe across said cutting edge along a path that is convex rearwardly of the heel from lift surface to breast-line center, said supporting means also being movable to swing said heel laterally, and to displace said heel transversely, of said tool for completing the breasting of said heel to the opposite outer ends of the breast line.

17. In a machine for breasting attached heels, a breasting tool having a cutting edge, and a shoe carrier for supporting a shoe and its attached heel for feeding movement relative to said tool for breasting said heel, said carrier being mounted for rectilinear movement toward said tool, tilting movement relative to said tool, swinging movement sidewise of said tool, and transverse movement in a direction to move the heel away from said tool. 5
18. That improvement in methods of breasting attached heels which consists in first forming a breast surface on the heel from top lift to breast-line center by effecting a relative heightwise feeding movement of said heel and the cutting edge of a breasting tool from top lift to breast-line center and subsequently completing said breast surface to the remaining parts of the breast line by causing relative sidewise movement of said heel and said tool along the 15 breast line from the breast-line center to each opposite end thereof. 10
19. That improvement in methods of breasting attached heels which consists in first forming a substantially vertically straight and laterally concave breast surface on the heel from top lift to breast-line center by effecting a relative heightwise feeding movement of said heel and the curved cutting edge of a breasting tool along a curved path from top lift to breast-line 20 center and subsequently completing said breast surface to the remaining parts of the breast line by causing a relative sidewise movement of said heel and cutting edge of said tool along the breast line from breast-line center to each opposite end thereof. 25
20. That improvement in methods of breasting attached heels which consists in first forming a substantially vertically straight and laterally concave breast surface on the heel from top lift to breast-line center by effecting a relative heightwise feeding movement of said heel and the curved cutting edge of a breasting tool along a path which is convex forwardly of the heel and extending from top lift to breast-line 30 center, and subsequently completing the breast surface to the remaining parts of the breast line by causing a combined relative sidewise and separating movement of said heel and the cutting edge of said breasting tool. 35
21. That improvement in methods of breasting attached heels which consists in first forming a substantially vertically straight and laterally concave breast surface on the heel from top lift to breast-line center by effecting a relative heightwise feeding movement of said heel and the curved cutting edge of a breasting tool along a path which is convex forwardly of the heel and extending from top lift to breast-line 40 center and subsequently completing the breast surface to opposite ends of the breast line by causing a relative sidewise displacement of said heel and said tool and simultaneously effecting a relative separating movement of said heel and the cutting edge of said tool. 45
22. That improvement in methods of breasting attached heels of the type which widen appreciably from top lift to breast line which consists in first forming a substantially vertically straight and laterally concave breast surface having straight side edges on the heel from top lift surface to breast-line center by feeding the heel across the curved cutting edge of a transversely operating breasting tool from top lift to 50
- breast-line center along a path that is convex forwardly of the heel, and subsequently completing the breast surface to opposite ends of the breast line by causing a relative sidewise movement of said heel and the cutting edge of said tool along a path having a curvature substantially the same as that of the shank of the shoe the heel of which is being breasted and simultaneously effecting a separation of said heel and said tool sufficient to insure a continuance of the straightness of the side edges of said breast surface to the breast line ends. 55
23. That improvement in methods of breasting attached heels to produce breast surfaces having straight side edges which consists in feeding the heel across the cutting edge of a breasting tool from top lift to breast-line center to breast the heel from top lift to breast-line center and subsequently feeding said heel sidewise across the tool from breast-line center to each opposite end of the breast line to complete the breasting of said heel along the entire breast line. 60
24. That improvement in methods of breasting attached heels to produce breast surfaces having straight side edges which consists in feeding the heel across the cutting edge of a breasting tool along a curved path from top lift to breast-line center to breast said heel from top lift to breast-line center and subsequently feeding said heel sidewise across said cutting edge from breast-line center to each opposite end of the breast line to complete the breasting of said heel along the entire breast line. 65
25. That improvement in methods of breasting attached heels to produce breast surfaces having straight side edges which consists in feeding the heel across the curved cutting edge of a breasting tool along a curved path from top lift to breast-line center to breast said heel from top lift to breast-line center, and subsequently feeding the heel sidewise of the tool along a path having a curvature substantially the same as that of the shank of the shoe the heel of which is being breasted to complete the breasting of said heel from breast-line center to each opposite end of the breast line. 70
26. That improvement in methods of breasting attached heels to produce breast surfaces having straight side edges which consists in feeding the heel across the curved cutting edge of a breasting tool along a curved path from top lift to breast-line center to breast said heel from top lift to breast-line center, and subsequently feeding said heel sidewise across said cutting edge along a path having a curvature substantially the same as that of the shank portion of the shoe the heel of which is being breasted and simultaneously withdrawing the heel from said curved cutting edge to complete the breasting of said heel from breast-line center to each opposite end of the breast line. 75
27. In a machine for breasting attached heels a breasting tool having a cutting edge operable transversely of the heel to cut a concave breast thereon, carriage means mounted for movement toward the cutting edge of said tool, supporting means for an attached heel movable with said carriage to pass a heel across said cutting edge, and means for tilting said supporting means during movement of said carriage to cause said heel to be moved across said cutting edge in a curved path. 80
28. In a heel-breasting machine, in combination, a frame, a breasting tool, means for feeding

an attached heel to said tool along a curved path, said means comprising a carriage mounted on said frame for movement toward said tool, a carrier mounted on said carriage for tilting movement thereon, an adjustable arm on said carrier, and means associated with said frame and engaging said arm, said arm and said last-named means being constructed and arranged to effect tilting of said carrier on said carriage during movement of said carriage and carrier toward said tool.

29. In a heel-breasting machine, in combination, a breeding tool adapted to cut transversely of an attached heel and constructed and arranged to produce a substantially vertically straight and laterally concave breast from lift surface to breast line without interference with other portions of a shoe, means for feeding an attached heel to said tool along a curved path, and means for varying the curvature of said path.

30. A heel-breasting machine comprising, in combination, a breeding tool, carriage means movable toward said tool and arranged for side-wise swinging movement relative thereto, means for limiting carriage movement toward said tool and for preventing said swinging movement until said carriage movement is completed, supporting means for holding an attached heel for breeding by said tool mounted on said carriage means for tilting movement thereon, and means for shifting said carriage transversely of said tool during said swinging movement, said several means being constructed and arranged to permit an initial feeding of a heel into said tool for breeding said heel from lift surface to breast-line center and a subsequent swinging and transverse shifting of said heel to complete the breeding of said heel on each side of the breast-line center for the full width of said heel.

31. A heel-breasting machine comprising, in combination, a breeding tool, carriage means movable toward said tool and arranged for side-wise swinging movement relative thereto, supporting means for holding an attached heel for breeding by said tool mounted on said carriage means for tilting movement thereon, and means for shifting said carriage transversely of said tool during said swinging movement, said several means being constructed and arranged to permit an initial feeding of a heel into said tool for breeding said heel from lift surface to breast-line center and a subsequent swinging and transverse shifting of said heel to complete the breeding of said heel on each side of the breast-line center for the full width of said heel.

32. A heel-breasting machine comprising, in combination, a breeding tool, carriage means movable toward said tool and arranged for side-wise swinging movement relative thereto, supporting means for holding an attached heel for breeding by said tool mounted on said carriage means for tilting movement thereon, cam means for shifting said carriage transversely of said tool during said swinging movement, and means for varying the shifting action of said cam, said several means being constructed and arranged to permit an initial feeding of a heel into said tool for breeding said heel from lift surface to breast-line center and a subsequent swinging and transverse shifting of said heel to complete the breeding of said heel on each side of the breast-line center for the full width of said heel.

33. In a heel-breasting machine, in combination, a breeding tool, a carriage movable toward said tool and swingable laterally with respect to said tool, means for limiting movement of said carriage toward said tool and for controlling the lateral swing of said carriage, and means for preventing swinging of said carriage before the limit of movement of said carriage toward said tool is substantially reached.

34. In a heel-breasting machine, in combination, a breeding tool, a carriage movable toward said tool and swingable laterally with respect to said tool, adjustable means for limiting movement of said carriage toward said tool, and means for preventing swinging of said carriage before the limit of movement of said carriage toward said tool is substantially reached.

35. In a heel-breasting machine, in combination, a frame, a heel-breasting tool, a carriage mounted on said frame for swinging movement relative to said tool, means for supporting said carriage comprising a cam mechanism for lifting said carriage during said swinging movement, and spring means for relieving said cam means of the major part of the carriage load.

36. In a heel-breasting machine, in combination, a frame, a breeding tool, carriage means movable toward said tool and carrying a tiltable carrier, said carriage means being mounted for swinging movement relative to said tool, means for moving said carriage transversely of said tool during said swinging movement, said last-named means comprising a cam rotatable with and supporting said carriage, a fixed roller cooperating with said cam, and means interposed between said carriage and cam for varying its moving effect.

ERASTUS E. WINKLEY.
